United States Patent Office

Des. 178 365

Patented July 31, 1956

178,365

STEREO CAMERA

Frederick W. Hertzler, Detroit, Mich., assignor to Argus
Cameras, Inc., Ann Arbor, Mich., a corporation of
Michigan

Application March 12, 1956, Serial No. 40,536

Term of patent 14 years

(Cl. D61—2)

FIG. 1

FIG. 2

Fig. 3

Fig. 4

Fig. 5

Figure 1 is a front elevational view of a stereo camera embodying my new design.

Figure 2 is a rear elevational view thereof.

Figure 3 is a top plan view of the camera of Figures 1 and 2.

Figure 4 is a bottom plan view of the camera of Figures 1-3.

Figure 5 is one side elevation view of the camera of Figures 1-4.

Figure 6 is a side elevation view of the camera of Figures 1-5 from the side opposite that of Figure 5.

I claim:

The ornamental design for a stereo camera, substantially as shown.
